UNITED STATES PATENT OFFICE.

HARRY E. CILLEY AND CHARLES S. GOODING, OF BOSTON, MASSACHUSETTS;
SAID GOODING ASSIGNOR TO EDWARD C. JUDD, OF SAME PLACE.

MACHINE FOR LEVELING SHOE-SOLES.

SPECIFICATION forming part of Letters Patent No. 656,764, dated August 28, 1900.

Application filed July 12, 1899. Serial No. 723,587. (No model.)

To all whom it may concern:

Be it known that we, HARRY E. CILLEY and CHARLES S. GOODING, citizens of the United States, residing at Boston, in the county of 5 Suffolk and State of Massachusetts, have invented new and useful Improvements in Machines for Leveling Shoe-Soles, of which the following is a specification.

This invention relates to the type of machines for leveling shoe-soles described and shown in Letters Patent Nos. 563,666 and 591,766, issued, respectively, July 7, 1896, and October 12, 1897, to Judd and Cilley.

The chief objects of the present invention 15 are to generally improve and simplify the prior machines and facilitate their operation, whereby it is possible for any operator or workman to properly manage the same, adapt them for shoes of varying size and soles of 20 different contour, and obtain the best results.

The invention also has for its object to provide novel, simple, and effective means for automatically raising a leveling-roll from the shoe-sole during the leveling operation.

25 The invention also has for its object to provide novel means for varying the time at which the leveling-roll is automatically raised from the shoe-sole, whereby the point on the sole at which it is desired to raise the roll from 30 the sole can be changed to suit the conditions required.

The invention also has for its object to provide novel means for varying the extent to which the roll is automatically raised from 35 the sole.

The invention also has for its object to provide new and improved means for mounting the shank-roll and enabling it to operate correctly according to the conditions required 40 in acting upon sole-shanks that vary in contour.

The invention also has for its object to provide new and improved means for locking the horizontally or laterally movable shoe-supporting arm to and unlocking it from the rocking jack-frame.

The invention also has for its object to provide novel and simplified means for vibrating the fore-part and shank rolls during the leveling operation.

To accomplish all these objects, our inven-

tion involves the features of construction, the combination or arrangement of parts, and the principles of operation hereinafter described and claimed, reference being made to the accompanying drawings, in which—

Figure 1 is a side elevation of a sole-leveling machine embodying our invention. Fig. 2 is a detail side view of the bell-crank lever for actuating the carriers of the fore-part and shank rolls. Fig. 3 is a front elevation of the same. Fig. 4 is a detail side view of the cam for actuating the locking device by which the laterally-movable shoe-supporting arm or frame is locked to and unlocked from the jack-frame. Fig. 5 is a detail vertical sectional view taken on the line 5 5, Fig. 1. Fig. 6 is a detail horizontal sectional view taken on the line 6 6, Fig. 1. Fig. 7 is a detail side view of the adjustable cam for automatically raising the shank-roll at recurring intervals. Fig. 8 is a detail broken plan view showing the devices by which the shank-roll is mounted on the vibratory carrier-frame. Fig. 9 is a front elevation of the same. Fig. 10 is a vertical sectional view taken on the line 10 10, Fig. 9; and Fig. 11 is a diagrammatical view of a shoe-sole having a crooked or irregular shank.

In order to enable those skilled in the art 80 to make and use my invention, we will now describe the same in detail, referring to the drawings, wherein the numeral 1 indicates a suitable main frame having bearings at its base portion, in which a driving-shaft 2 is 85 journaled. This shaft is geared to and drives a gear-wheel 3, secured to a shaft 4, having an eccentric 5, connected by a rod 6 and eccentric-strap 7 with an arm 10, forming a part of the longitudinally-rocking jack-frame 90 12. The arm 10 is preferably curved, and the connecting-rod 6 is pivoted to the arm by a pivot, as at 13. The gear-wheel 3 is driven at comparatively-slow speed and by the connections set forth slowly rocks the jack-frame, which latter carries the laterally-movable shoe-supporting arm or frame 14, one or more, pivoted at 15, and carrying heel and toe posts 16 and 17, preferably constructed and adjustable as in either of the former 100 patents, but which can be of any other suitable type. The ordinary or any suitable

treadle 18 is connected by the usual vertical spring-rods 19 and 20 with the pivoted yoke-shaped frames 21 and 22 that support the fore-part and shank rolls 23 and 24. As in 5 the prior machines referred to and others of this class or type, the springs forming parts of the spring-rods 19 and 20 serve to permit the rolls 23 and 24 to yield upward during the leveling operation, and when the spring- 10 rods 19 and 20 are released by unlocking the treadle the said springs and the counterbalance-weight 59^a cause the rolls to rise. The shank-roll mounted on carrying devices in the yoke-shaped frame 22 is vibrated by a 15 bell-crank lever having a vertical arm 25 and a horizontal arm 26. This lever is pivoted at its angle to a shaft 27, mounted in a bearing on the main frame, and its horizontal arm is pivoted to the upper end of a connecting- 20 rod 28, engaged at its lower end with an eccentric 29 on the driving-shaft 2, whereby the lever is more or less swiftly vibrated. The vertical arm of the bell-crank lever is provided with two bearings 30 and 31, Figs. 2 25 and 3, at different heights or levels. The lower bearing 30 is designed to be pivotally connected with and vibrate the carrying devices of the shank-roll 24 on the yoke-shaped frame 22, while the upper bearing connects 30 by a rod 32 with the carrier or frame 33, which directly carries the fore-part roll 23, the construction being such that as the bell-crank lever is rocked or vibrated the shank-roll is vibrated in the pivotally-mounted yoke- 35 shaped frame 22 and the fore-part roll is oscillated or vibrated in the pivotally-mounted yoke-shaped frame 21. These yoke-shaped frames may be pivotally mounted in any suitable manner—for instance, as in the former 40 patents.

The yoke-shaped frame 22, supporting the carrying devices of the shank-roll, is automatically and positively raised at recurring intervals to raise the shank-roll from contact 45 with the shoe-sole during the leveling action of said shank-roll, as we will now explain, such automatic raising of the shank-roll from contact with the shoe-sole being entirely independent of the action of the springs in 50 or forming parts of the spring-rods 19 and 20. The purpose of this operation of raising the shank-roll from the sole of the shoe during the leveling operation is to insure that the heel-seat of the shoe will not be leveled. It 55 is not desirable that the heel-seat of the shoe should be leveled, and it will be readily seen that if the fore-part roll is carried onto the shank of a small-size shoe there will not be sufficient room in the shank for both the 60 shank-roll and the fore-part roll. Therefore according to our invention mechanism is provided for raising the shank-roll from the shoe-sole, so that it will not pass over and level the heel-seat or fall off the end of the shoe. 65 A bell-crank lever 34 is pivoted at its angle portion on the shaft 35, mounted in the top of the main frame. The lever comprises two

arms 36 and 37, the latter bearing against the cam-shaped edge of a cam 38 and the former carrying a vertically-adjustable set-screw 39, 70 bearing against a bracket 40 on the frame 22. The cam is substantially a segmental ring, Fig. 10, mounted on the periphery of a worm-gear 41, keyed to a rock-shaft 42, journaled in the main frame, and the ends of the ring 75 are provided with bearings 43, in which is journaled a rotary worm 44, the shaft of which has a finger-piece or handle 45 and lock-nut 46. The worm-gear is provided at its inner side with an annular flange 47, Fig. 80 9, and at its outer side with an attachable and detachable ring 48, the cam-ring being confined between the flange 47 and ring 48. The rock-shaft 42 has a crank-arm 49, pivotally connected by a link 50 with the arm 10 of the 85 jack-frame, and consequently as the latter rocks an oscillating motion is imparted to the cam 38, and its cam edge acting on an anti-friction-roller 51 at the end of the arm 37 of the bell-crank lever 34 causes the arm 36 90 thereof to rise, whereby the yoke-shaped frame 22 and shank-roll 24 are caused to correspondingly rise. The extent to which the frame 22 is lifted and shank-roll 24 is raised independently of the action of the springs in 95 or forming parts of the spring-rods 19 and 20 is regulated by the adjustable set-screw 39, as will be obvious. The time when the lever 34 is operated and the frame 22 and shank-roll are raised can be varied to suit the conditions required through the medium of the worm 44, engaging the worm-gear 41. By turning the worm in the proper direction by its finger-piece or handle the cam will be turned the required distance around the 100 worm-gear to obtain the necessary adjustment of its cam edge relatively to the roller 51 on the end of the arm 37 of the bell-crank lever 34, after which the worm is locked by the lock-nut 46. It is evident, therefore, that the time 110 at which the lever 34 is actuated to lift the shank-roll can be varied at will or changed with relation to the motion of the jack-frame and the point on the shoe-sole at which it is desired the shank-roll should rise therefrom. 115 The rocking jack-frame is secured to a rocking jack-shaft 52, carrying a cam 53, having in its inner face a cam-shaped race 54, (best seen in Fig. 4,) constructed at its ends with rest portions 55 and 56. The cam has an arm 120 57, pivotally connected by a link 58 with the usual lever 59, carrying the counterweight 59^a, and pivotally connected at its front end with the treadle 18 by a link 60. The race 54 of the cam 53 is engaged by a roller-stud 125 61 on the arm 62 of a bell-crank lever 63, pivoted at its angle, as at 64, and having its other arm 65 slotted at its rear extremity to receive a pin 66, secured to a locking-bolt 67, Fig. 8, movable vertically in a socket formed 130 in a part of the jack-frame, so that the bolt will lie directly under and engage a locking notch or recess 68 in the under side of the rear end of the shoe-supporting arm 14 when

it is in normal position for a shoe-sole to be leveled. When the treadle 18 is depressed and held down, the cam 53 will be turned so that the central part of the rest portion 56 of 5 the cam-race will be presented to the roller-stud 61 of the bell-crank lever 63, and therefore the jack can rock without the lever 63 being oscillated, in consequence of which the bolt 67 remains in engagement with and locks 10 the shoe-supporting arm to the jack-frame; but when the treadle is released and thrown upward by the weighted lever 59 the cam 53 will be turned so that the acting part of the cam-race will depress the lever 63 and cause 15 it to retract the bolt from locking engagement with the shoe-supporting arm, whereupon the latter can be moved or swung laterally. After the treadle is raised the roller-stud 61 will be presented to the rest portion 20 55 of the cam-race, the jack may rock without moving the lever 63 in the manner required to actuate the bolt 67, and the bolt will be held retracted. The upper end of the locking-boit is double beveled, and it is pressed 25 upward by a spring 69 to snap into engagement with the shoe-supporting arm when it is moved or swung to normal position or in alignment with the jack-frame. The spring may serve to throw the bolt upward; but obviously the cam 53, acting on the lever 63, may 30 serve that purpose.

Referring now to Figs. 8, 9, and 10 of the drawings, the two-part shank-roll 24 is rotatably mounted in studs carried by segmentally-slotted holders or plates 85, arranged on 35 a plate 91, supported, through the medium of a pivot 92, by a carrier 86, pivotally mounted on the upper and lower ends of a vertical pintle or pivot-pin 88, arranged in a bearing 40 89 of the carrier-frame 87. The carrier 86 is formed with a front depending arm or hanger 82, which extends rearwardly and forms the upper bearing for receiving the pintle or pin 89. A set-screw S is provided for impinging 45 against the pintle or pin to prevent it from falling through the bearing 89. By this construction the carrier 87, the plates 85, and the two - part shank - roll 24 are susceptible of 50 swinging in a horizontal plane, so that the axis of the roll may assume the positions indicated by the dotted lines 90 on a shoe-sole, the shank of which is of greater length at its inner sides than at its outer sides, as clearly shown in Fig. 11 of the drawings.

55 Our improved arrangement, in which the shank-leveling roll is mounted to swing in a plane parallel with the shank-face of the last, or, in other words, horizontally, as shown in the drawings, is of much advantage, as thereby 60 the shank may be leveled over its entire surface quickly and satisfactorily without manipulation either of the shoe or the leveling mechanism. As well, known the shank portion of a shoe is longer at its inner edge than 65 its outer edge. By reason of our novel arrangement the movement of the outer end of the shank-leveling roll will be arrested or

stayed at the forward limit of the outer side of the shank of the shoe, and said roll will swing in a plane parallel with the shank of 70 the shoe and its inner end continue its travel to the forward limit of the inner edge of the shank. Thus the entire surface of the shank may be leveled without manipulation either of the shoe or the leveling mechanism and 75 without crushing any portion of the shank.

The plate 91 at the front on the carrier 86 is mounted on a pivot-screw 92, passing through the lower end of the hanger 82, and the segmentally-slotted plates 85, in which the two-part roll is journaled, are connected to the plate 91, so that the shank-roll by reason of 80 its connection with the plate 91 is capable of swinging in a vertical plane to accommodate varying conditions of work and varying contours of shoe-shanks. The segmentally-slotted plates are adjustable on the plate 91 and are held in adjusted position by means of thumb-screws 93, engaging screw studs 94, projecting from the plate 91, so that the segmentally-slotted holders or plates may be independently adjusted in the arcs of a circle on 85 the plate 91 to vary the angle of inclination of the axis of each part of the two-part shank-roll, thereby adapting the roll to properly 90 operate upon shoe-shanks which vary in contour or to suit other conditions that may arise. The adjustability of the inclination of the axis of each part of the shank-roll is shown in dotted lines in Fig. 9 of the drawings. 100

The means described and shown for varying the angle of inclination of the axis of the shank-roll may be employed in connection with a fore-part roll to adapt it to soles that vary in contour at the fore part. 105

The horizontal and vertical swinging movements of the shank-roll 24 described are automatic, as will appear.

The mechanism for automatically raising the shank-roll at predetermined or recurring 110 intervals may be applied to either of the machines disclosed by the Letters Patent herein-before referred to. In the former machines the shank-roll was given a reciprocating motion (in addition to its vibratory motion) of, 115 say, six inches, while the shoe moved a distance of, say, nine inches. The difference of three inches is the distance the shank-roll traveled upon the shoe-sole. It is inconvenient to limit the travel of the shank-roll upon 120 the sole-shank, and the shank-roll is therefore liable to travel onto the breast of the heel and round off the edges thereof. This is effectually avoided by the present machine, as the reciprocating movement of the shank-roll is eliminated, the shank-roll is lifted at such point relative to the sole as may be desired, and very simplified means are provided to place the machine under control of the operator and enable any workman to readily 125 manage the machine and adapt it to shoes of different sizes.

Having described our invention, what we claim is—

1. The combination with a jack, a sole-leve-
eling roll, and a spring-rod for yieldingly de-
pressing the roll upon the shoe-sole, of auto-
matically-actuated devices independent of
the spring in, or forming a part of said spring-
rod, operating to positively raise the leveling-
roll at intervals from contact with the shoe-
sole during the leveling operation.
2. The combination with a movable jack,
10 and a sole-leveling roll, of devices operated
by the jack and automatically raising the roll
at predetermined or recurring intervals.
3. The combination with a jack, a fore-
part-leveling roll, a shank-leveling roll,
15 frames carrying said rolls, spring-rods con-
nected with said frames, and a treadle for
pulling the spring-rods downward, of auto-
matically-actuated devices independent of
the spring in, or forming part of, the spring-
20 rod for depressing the shank-roll-carrying
frame, operating to raise the shank-leveling
roll at intervals from contact with the shoe-
sole during the leveling operation.
4. The combination with a rocking jack,
25 and a sole-leveling roll, of mechanism actuated
at intervals by the rocking jack to raise
the roll from the sole being operated on.
5. The combination with a jack, and a sole-
leveling roll, of a movable cam, means for
30 moving the cam, and devices automatically
actuated by the cam and operating to posi-
tively raise said roll at intervals from the
shoe-sole during the leveling operation.
6. The combination with a jack, a sole-leve-
35 eling roll, a spring-rod, and a treadle for de-
pressing the spring-rod and leveling-roll, of
automatically-actuated devices independent
of the spring in, or forming part of said spring-
rod, operating to positively raise the roll at
40 intervals from contact with the shoe-sole dur-
ing the leveling operation, and devices for
varying the extent to which said roll is raised.
7. The combination with a jack, and a sole-
leveling roll, of a movable cam, means for
45 moving the cam, devices automatically actuated
by the cam and operating to positively raise
said roll at intervals from the shoe-sole
during the leveling operation, and devices
for varying the time at, and extent to, which
50 the roll is raised.
8. The combination with a rocking jack,
and a sole-leveling roll, of devices operated
by the jack and automatically raising the roll
at intervals, and devices for varying the time
55 at, and extent to, which the roll is raised.
9. The combination with a movable jack,
a sole-leveling roll, and a vertically-movable
frame sustaining the roll, of a cam moved by
the jack, and a device actuated at intervals
60 by the cam to raise said frame and roll.
10. The combination with a movable jack,
a sole-leveling roll, and a vertically-movable
frame sustaining the roll, of a cam moved by
the jack, a device actuated at intervals by
65 the cam to raise said frame and roll, and
- means for varying the time at which the cam
acts on said device to raise the frame and roll.
11. The combination with a movable jack,
a roll and a vertically-movable frame sustain-
ing the roll, of a cam moved by the jack, a 70
lever actuated at intervals by the cam to
raise the frame and roll, means for adjusting
the cam to vary the time at which said frame
and roll are raised, and a device carried by
the lever to vary the extent to which the frame 75
and roll are raised.
12. The combination with a movable jack,
a roll, and a vertically-movable frame sus-
taining the roll, of a cam moved by the jack,
a lever acted on at intervals by the cam to 80
raise the frame and roll, and a worm-gear and
a worm for turning the cam to vary the time
it operates the lever to raise said frame and
roll.
13. The combination with a movable jack, 85
a roll, and a vertically-movable frame sus-
taining the roll, of a cam, means for moving the
cam, a bell-crank lever having one arm pro-
vided with an adjustable screw bearing
against said frame and the other arm ar-
ranged to be operated by the cam, and a 90
worm-gear and a worm for adjusting the cam.
14. The combination with a movable jack,
a shank-roll, and a frame sustaining the roll,
of a rock-shaft, a link connecting the jack 95
with the rock-shaft, a worm-gear on the shaft,
a cam on the worm-gear, a worm connected
with the cam and engaging the worm-gear, a
lever acted on at intervals by the cam to raise
said frame and roll, and means for varying 100
the extent to which the lever raises the frame
and roll.
15. The combination with a rocking jack,
and a shank-roll, of a rock-shaft, a link con-
necting the jack with the rock-shaft, a worm- 105
gear on said shaft, a cam on the worm-gear,
a worm connected with the cam and engag-
ing the worm-gear, and devices operated at
intervals by the cam to raise said roll.
16. In a sole-leveling machine, a shank- 110
leveling roll mounted to swing in a plane par-
allel with the shank-face of the last, substan-
tially as described.
17. The combination of a horizontally-
swinging carrier, segmentally-slotted plates 115
swinging horizontally with said carrier, ad-
justing devices for securing the slotted plates
in their adjusted position, and a leveling-
roll carried by said plates.
18. The combination with a vibratory 120
frame, a vertical pintle or pivot-pin thereon,
a horizontally-swinging carrier engaged with
the pintle or pivot-pin, a vertically-rocking
plate pivotally mounted on said carrier, ad-
justable roll-holding plates mounted on the 125
rocking plate, and a leveling-roll carried by
the adjustable plates.
19. The combination with a jack-frame,
and a movable shoe-supporting arm or frame
mounted thereupon, of a locking device for 130

engaging and locking the arm or frame to the jack-frame, a cam, means for shifting the cam, and means operated by the cam to disengage the locking device from said arm or frame.

20. The combination with a rocking jack-frame, a movable shoe-supporting arm or frame mounted thereupon, and a jack-frame shaft, of a locking device for engaging and locking the arm or frame to the jack-frame, a cam on the jack-frame shaft, a treadle for shifting the cam, and means operated by the cam for disengaging the locking device from said arm or frame.

15 21. The combination with a movable jack-frame, and a movable shoe-supporting arm or frame mounted thereupon, of a locking device for engaging and holding the arm or frame to the jack-frame, a treadle and means 20 thrown into action by the treadle to disengage the locking device from said arm or frame.

22. The combination with a movable jack-frame, and a movable shoe-supporting arm 25 or frame on the jack-frame, of a locking device for engaging and disengaging said arm

or frame, a cam, and a lever engaged with said cam and with said locking device and actuated by the jack-frame and cam to disengage the locking device from the arm or frame. 30

23. The combination with a movable jack, and a movable shoe-supporting arm or frame on the jack, of a locking device for engaging and disengaging said arm or frame, a lever connected with the locking device, a cam engaging the lever, and a treadle connected with the cam. 35

24. The combination with the fore-part roll, the shank-roll, and carriers for the rolls, of a sole-leveling machine, of a single bell-crank lever having one arm provided with two bearings connected respectively with said carriers, and means for vibrating said lever and thereby vibrating both rolls. 40

In testimony whereof we have hereunto set 45 our hands in presence of two subscribing witnesses.
